UNITED STATES PATENT OFFICE.

ORLANDO R. ERWIN, OF FOREST HILLS, NEW YORK, ASSIGNOR TO FOAMITE-CHILDS CORPORATION, OF NEW YORK, N. Y., A CORPORATION OF DELAWARE.

FIRE-EXTINGUISHING APPARATUS.

Application filed April 30, 1921. Serial No. 465,695.

To all whom it may concern:

Be it known that I, ORLANDO R. ERWIN, a citizen of the United States, and resident of Forest Hills, in the county of Queens and 5 State of New York, have invented certain new and useful Improvements in Fire Extinguishing Apparatus, of which the following is a specification.

This invention relates to a fire extinguishing apparatus and more particularly to an apparatus of the type adapted for the storing of chemical component solutions and in which the solutions are comixed in time of fire for the production of a fire extinguishing medium such as foam, and has 10 special reference to the provision of a large capacity fire extinguishing apparatus such as a 40 gallon Foamite apparatus in which the component solutions are stored without 15 liability of accidental comixture and in which the intermixture of the component solutions in time of fire is automatically regulated for the controlled generation of 20 an efficient fire extinguishing foam compound.

Fire extinguishing apparatus of the type referred to is adapted to be mounted and transported on a truck such as a two-wheeled truck, for example, the apparatus being thus 25 transportable to a region adjacent a fire, the apparatus being adapted to be set into activity by inversion or tilting. Upon inversion of the apparatus the solutions stored therein are comixed, the solutions and the 30 foam resulting from their intermixture discharging through an extended hose section connected to the apparatus, completion of solution comixture taking place in the said 35 hose section, the resultant foam being discharged through a nozzle connected to the 40 hose. It has been found that in this type of apparatus, if the intermixture of the component solutions is controlled in a pre-determined manner, the solutions may be 45 gradually fed for comixture in their proper volumetric ratio or proportion, such solution discharging into the hose section in the desired proportionate volumes with the result that the comixture that takes place 50 in the hose section produces a foam substantially free from any unmixed component solution. My present invention therefore comprehends the provision of such a fire extinguishing apparatus in which means are 55 provided for effecting a regulated solution

comixture and in which the parts are so structurally related that efficient solution comixture and foam generation take place, with the resulting production of an efficient foam compound.

A desideratum in a transportable fire extinguishing apparatus of the above referred to type is the provision of an apparatus in which splashing and accidental intermixture of the component solutions is effectively 60 prevented. In conveying such apparatus on a wheeled truck to the scene of a fire, the apparatus is subjected to considerable shaking and vibration, the component solutions stored in independent compartments 65 or tanks in the apparatus being thus subjected to liability of splashing and resulting solution intermixture. Means must therefore be provided for preventing any such accidental comixture which would 70 result in a misproduction or misgeneration of the foam compound. A convenient and efficient means comprehends the utilization of 75 manually operable valve means in the form of a stopple cooperating with one of the solution compartments or tanks, normally 80 closing and sealing the same against the other component solution. In this manner the apparatus may be safely handled and freely moved about without fear of foam 85 misproduction. However, in moving the extinguisher about from place to place during storage use, for example, movement in 90 splashing the solutions in the tanks is bound to take place, films of solutions and especially the acid solution forming over the 95 stopple or valve seat, crystallization of the solution films taking place at such valve seat, resulting in the incrustation of the stopple valve and rendering the valve subject to difficulty of operation in time of fire. My 100 invention therefore comprehends the provision of a fire extinguishing apparatus in which not only is intermixture of the solutions prevented, but in which splashing is reduced and in which crystallization at the 105 valve seat is effectively minimized, with the resulting provision of an extinguisher capable of facility of operation even after long storage use.

The principal objects of my present invention therefore include, in addition to the provision of a fire extinguishing apparatus in which solution feeding is controlled for regulated intermixture in the apparatus and 110

in the discharge hose connected thereto and forming part thereof, the provision of such an engine which may be safely transported from place to place, intermixture of solutions being prevented, splashing of solutions being reduced and crystallization of the solution films at the stopple seat being minimized; the further provision of such an apparatus in which the internal foam pressure 10 is distributed and equalized, aiding in a regulated solution flow and gradual solution comixture and the provision of apparatus of this nature in which the parts are associated to the end of providing a strong, durable apparatus capable of a facility of 15 charging, cleaning and discharging operations.

To the accomplishment of the foregoing and such other objects as may hereinafter 20 appear, my invention consists in the elements and their relation one to the other, as hereinafter particularly described and sought to be defined in the claims, reference being had to the accompanying drawings 25 which show a preferred embodiment of my invention and in which:

Figure 1 is a longitudinal cross sectional view of my improved apparatus,

Figure 2 is a cross sectional view on the 30 line 2—2 of Figure 1, with the inner receptacle removed, and

Figures 3 and 4 are respectively enlarged plan and cross sectional elevational views of the inner receptacle with parts broken away.

Referring to the drawings, the apparatus 35 comprises an outer shell generally designated as 10, having a cylindrical body 11 and a dished bottom 12, preferably formed integral therewith, the bottom 12 being provided with a depressed portion 13 adapted 40 to supportingly receive the inner receptacle, as will appear more in detail hereinafter, the outer shell being provided with a preferably dome shaped top 14, which may be brazed to the upper portion of the cylindrical walls 11, the top 14 being in turn provided with a threaded neck 15, removably receiving a hand wheel 16, the said hand wheel being preferably provided with opposed horns 17 acting as grip members for 45 rotating the handle 16 to remove or replace the same on the top 14, a gasket 18 being preferably provided for the purpose of securing an efficient closure between the hand wheel and the dome shaped top 14. For the 50 purpose of mounting the outer shell 10 upon a truck, such as a two-wheeled truck for example, an axle band 19 may be provided, the said axle band being preferably shrunk onto the cylindrical walls 11 of the shell 10, as shown particularly in Figure 1 of the drawings.

The outer shell 10 is intended for the reception of a B or basic component solution, 55 the A or acid component solution being con-

tained in an inner receptacle 20 provided for this purpose, the said solutions having compositions preferably as disclosed in the patent to Walker, No. 1,259,813 of March 19, 1918, the said inner receptacle 20 being 70

firmly supported within the outer shell 10 and being supplied with a dished bottom 21 received and supported by the depressed portion 13 in the outer shell bottom 12. The inner and outer receptacles 20 and 10 re- 75 spectively receive the acid and basic component solutions, the said solutions being intended for comixture in time of fire for the production of a fire extinguishing foam.

I have found that in an apparatus of this type that if the intermixture of the component solutions is controlled in a predetermined manner for the intermixture of the solutions in a desired volumetric ratio or proportion, that an efficient foam compound 85 may be produced. I have further found that by regulating the solution flow in a predetermined manner, so as to provide the desired volumetric intermixture, that comixture in an extended hose line connected to an 90 apparatus of this type may be effectively controlled for the production of a foam substantially free from any unmixed component solution. To this end I provide baffle plates or partitions having solution ports of 95

the desired configuration, these ports being so interrelated and associated with foam discharge means in the engine as to effect the desired result. Accordingly, I provide an outer partition 22 which may be welded, for 100 example, to the dome shaped top 14, as shown at 23, the partition 22 dividing the outer shell 10 into a solution compartment B and a mixing chamber 24. The partition 22 is provided with solution port means, the present form of my invention comprehending a single port 25 of a predetermined area, the said port forming a communicating duct between the B solution compartment and the mixing chamber 24. The inner receptacle 20 is also provided with a similar partition and in the present form of my invention I prefer to provide a cage structure 26 having vertical walls 27, the said walls being provided with spaced solution openings 28; 110 the said cage structure 26 preferably taking the form of an integral casting provided with a horizontal partition 29 extending across the upper open end of the inner receptacle 20, the casting being connected to 115 the walls of the said receptacle 20 as by being riveted thereto and shown particularly in Figures 1 and 4 of the drawings. The partition 29 is provided with a solution port 30 of predetermined configuration, the said solution port comprising an intercommunicating duct means between the A solution compartment and the mixing chamber 24.

The cage structure or casting is preferably provided with a threaded portion 31, which 120

125

130

is received by a tapped opening 32, preferably formed centrally in the partition 22, the inner receptacle 20 being thus insertable in the outer receptacle by rotating the said 5 inner receptacle, the tapped opening 32 receiving the thread 31, the inner receptacle in this manner being firmly supported at its upper end within the outer receptacle. With 10 this construction, upon inverting or tilting 10 of the apparatus, the solutions will flow from the A and B compartments in a controlled manner for regulated intermixture in the mixing chamber 24.

In this form of apparatus it is desired 15 that the solution comixture in the mixing chamber 24 be only in its formative stages, it being required that completion of co-mixture take place in an extended hose section connected to the mixing chamber 24. 20 The mixing chamber 24 is accordingly provided with a foam discharge outlet 33, the usual extended hose section (not shown) being connected to this outlet 33. Referring 25 to Figures 1 and 2 of the drawings, it will be seen that the foam outlet 33 is located angularly to one side of the solution outlet 25, these outlets being relatively displaced in the manner shown in Figure 2 for the 30 purpose of preventing any of the B or basic solution discharging from solution outlet 25 having direct egress through the discharge outlet 33, the degree or amount of displacement of the foam outlet 33 being so predetermined as to provide a construction 35 in which the solutions flowing through the solution ports 25 and 30 will intermix in the desired volumetric ratio in that portion of chamber 24 between the solution outlets and the discharge outlet 33, the intermixed and intermixing component solutions then discharging through the outlet 33, premixture in chamber 24 being only in its formative stages, completion of the comixture taking place in the extended hose line 40 connected to the discharge port 33.

In order to eliminate any accidental co-mixture between the component solutions in the A and B compartments incident to transportation of the device on a wheeled truck, I provide means for normally closing the A compartment and sealing the same against any of the solution in the B compartment. To this end I provide a 50 manually operable stopple valve comprising 55 a stopple 35 and a stem 36 connected thereto, the stem being provided with an operating handle 37, the said stem being threaded as at 38, the threaded portion 38 being received in a tapped boss 39 forming part of 60 the hand wheel 16, a stuffing box 40 being provided, as shown in Figure 1, to provide an anti-leak proof device. The partitions 22 and 29, besides functioning as a means for controlling solution flow in time of fire, 65 also function to minimize splashing of the

solutions, or movement of the solutions from out of the respective compartments. For the purpose of minimizing or reducing any crystallization of the solutions from taking place at the stopple seat, I supply provisions for reducing the cooperating area between the valve 35 and the opening with which it is associated. To this end the partition 29 is provided with an upstanding annular flanged portion 41, the said upstanding annular flange providing a seat for the stopple 35, the area of contact between stopple 35 and flange 41 being relatively small, this in cooperation with the baffle plate partition 29 minimizing crystallization and thus reducing stopple incrustation. In this manner and by this means a manually operable stopple valve is provided which forms an effective closure for the inner receptacle in time of storage use 85 and which is easily operable and is manipulated with facility in time of fire.

For the purpose of distributing and equalizing pressure resulting from the generation of foam in the fire extinguishing apparatus, 90 and for the purpose of facilitating a free flow of the solutions from the A and B compartments, I provide equalizing pressure means for both the inner and outer receptacles, said equalizing pressure means preferably taking the form of equalizing pressure tubes 42 and 43 respectively, the said tubes 42 and 43 being fixed to the partitions 29 and 22 respectively, as shown particularly in Figure 1 of the drawings, the said equalizing pressure tubes extending into the respective compartments and terminating adjacent the bottoms thereof, brackets 44 and 45 being provided and connected to the inner walls of the inner and outer receptacles 105 20 and 10 respectively, the said brackets 44 and 45 supporting the bottoms of the respective equalizing tubes 42 and 43. It will be noted that the annular upstanding flange forming the valve seat 29 encircles both the 110 solution port 30 and the equalizing pressure tube 42 so as to effectively close all the ports opening into the inner receptacle 20 and seal the same against the solution in the outer receptacle 10. For the purpose of facilitating 115 flushing or cleaning the apparatus, I may provide an opening 46 in the depressed portion 13 of the outer receptacle 10, the opening 46 being normally closed by a cap 47. I may also provide spaced pressure relief ports 48 in the hand wheel 16, as shown in Figure 1 of the drawings.

The operation and use of my apparatus will, in the main, be apparent from the above description thereof. In charging the 125 apparatus, the outer receptacle 10 is filled to a predetermined height with the B or basic solution, the inner receptacle 20 being then filled with the A or acid solution, the said inner receptacle being then inserted in 130

the outer receptacle, the bottom of the inner receptacle being supportingly received by the depressed portion 13 of the outer receptacle, the top of such inner receptacle 5 being supportingly received in the tapped partition 22 forming part of the outer receptacle. The hand wheel 16 is then threaded onto the threaded neck 15 of the top 14, the valve stopple 35 being then rotated to effect a closure between the said stopple and the flange valve seat 29. The apparatus may then be transported from place to place without the liability of solution intermixture and accidental misgeneration of foam, splashing of the solutions being reduced by the baffle plate partition structures 22 and 29, crystallization and in-crustation of the stopple being minimized by the cooperation of these parts in addition to the cooperation of the flanged seat 41 and the stopple 35. In time of fire the device is inverted or tilted, the stopple valve 35 rotated counterclockwise, the solutions in the A and B compartments being then free to flow from the respective compartments to the mixing chamber 24, the intermixture being regulated by the solution outlets 25 and 30 of predetermined area, comixture being initiated in the mixing chamber 24 for the production of the fire extinguishing foam, the foam and the unmixed solutions having egress through the discharge port 33 into an extending hose connected thereto, (not shown) completion of solution comixture taking place in such extended hose. By the regulated solution intermixture the desired volumetric ratio or proportion of solutions is co-mixed or brought into comixing relation, such desired proportion moving through the extended hose section, completion of comixture of such proportionate solutions there taking place for the generation of a foam free from any unmixed component solution. Some of the foam generated in the mixing chamber 24 will move up through the equalizing tubes 42 and 43 and exert pressure on the top levels of the solutions in the A and B compartments, such exerted pressure neutralizing or equalizing the back pressure of the foam at the solution ports 25 and 30 respectively, this resulting in a freedom of solution flow and thus aiding the desired solution comixture in the proper volumetric ratio.

From the above it will be apparent that I have provided a fire extinguishing apparatus in which solution feeding is controlled for regulated intermixture in the apparatus and in the discharge hose connected thereto for the production of an efficient foam stream, and in which accidental solution comixture is effectively prevented with the minimizing of splashing of the solutions and with the further minimiz-

ing of any tendency of stopple or valve in-crustation, this producing a device which is easily manned and operable in time of emergency use.

I claim:

1. A fire extinguishing apparatus of the type in which component chemical solutions are normally stored and are comixed for the production of a fire extinguishing medium, an outer receptacle for holding one of the component solutions, an inner receptacle for holding another of the component solutions, the outer receptacle being provided with a partition separating the said receptacle into a solution compartment and a mixing chamber; the said partition being provided with solution outlet means, the inner receptacle being also provided with a partition having solution outlet means and a manually operable valve means cooperating with said inner receptacle for normally closing its solution outlet means and being openable to permit solution communication from said inner receptacle to the said mixing chamber.

2. A fire extinguishing apparatus of the type in which component chemical solutions are normally stored and are comixed for the production of a fire extinguishing medium, an outer receptacle for holding one of the component solutions, a removable inner receptacle for holding another of the component solutions, the outer receptacle being provided with a partition separating the said receptacle into a solution compartment and a mixing chamber, the said partition supportingly receiving the removable inner receptacle and being provided with solution outlet means, the inner receptacle being also provided with a partition having solution outlet means and a manually operable valve means cooperating with said inner receptacle for normally closing its solution outlet means and being openable to permit solution communication from said inner receptacle to the said mixing chamber.

3. A fire extinguishing apparatus of the type in which component chemical solutions are normally stored and are comixed for the production of a fire extinguishing foam, an outer receptacle for holding one of the component solutions, an inner receptacle for holding another of the component solutions, the outer receptacle being provided with a partition separating the said receptacle into a solution compartment and a mixing chamber, the said partition being provided with solution outlet means and equalizing pressure inlet means, the inner receptacle being also provided with a partition having solution outlet means and equalizing pressure inlet means and a manually operable valve means cooperating with said inner receptacle for normally closing the solution outlet means and the equalizing pressure

- inlet means and being openable to permit solution communication from said inner receptacle to the said mixing chamber and foam communication from the mixing chamber to the inner receptacle.
4. A fire extinguishing apparatus of the type in which component chemical solutions are normally stored and are comixed for the production of a fire extinguishing foam, an outer receptacle for holding one of the component solutions, a removable inner receptacle for holding another of the component solutions, the outer receptacle being provided with a partition separating the said receptacle into a solution compartment and a mixing chamber, the said partition supportingly receiving the removable inner receptacle and being provided with solution outlet means and equalizing pressure inlet means, the inner receptacle being also provided with a partition having solution outlet means and equalizing pressure inlet means and a manually operable valve cooperating with said inner receptacle for normally closing the solution outlet means and the equalizing pressure inlet means and being openable to permit solution communication from said inner receptacle to the said mixing chamber and foam communication from the mixing chamber to the inner receptacle to the said inner receptacle.
5. A fire extinguishing apparatus of the type in which component chemical solutions are normally stored and are comixed for the production of a fire extinguishing medium, an outer receptacle for holding one of the component solutions, an inner receptacle for holding another of the component solutions, the outer receptacle being provided with a partition separating the said receptacle into a solution compartment and a mixing chamber; the said partition being provided with solution outlet means, the inner receptacle being also provided with a partition having solution outlet means and a manually operable valve cooperating with said inner receptacle for normally closing its solution outlet means and being openable to permit solution communication from said inner receptacle to the said mixing chamber, the partition of the inner receptacle being provided with an annular upstanding flange encircling the solution outlet means and forming a seat for the said valve.
6. A fire extinguishing apparatus of the type in which component chemical solutions are normally stored and are comixed for the production of a fire extinguishing foam, an outer receptacle for holding one of the component solutions, an inner receptacle for holding another of the component solutions, the outer receptacle being provided with a partition separating the said receptacle into a solution compartment and a mixing chamber, the said partition being provided with solution outlet means, a discharge port opening into the said mixing chamber, the said solution outlets and the discharge port being relatively displaced to permit a predetermined volumetric intermixture of the solutions to take place in the mixing chamber, the said partition being provided with solution outlet means and equalizing pressure inlet means, the inner receptacle being also provided with a partition having solution outlet means and equalizing pressure inlet means and a manually operable valve cooperating with said inner receptacle for normally closing the solution outlet means and the equalizing pressure inlet means and being openable to permit solution communication from said inner receptacle to the said mixing chamber and foam communication from the mixing chamber to the inner receptacle, the partition of the said inner receptacle being provided with an annular upstanding flange encircling the solution outlet means and the pressure equalizing inlet means and forming a seat for the said manually operable valve.
7. An inner receptacle for a fire extinguishing apparatus of the type in which component chemical solutions are normally stored and are comixed for the production of a fire extinguishing foam, the said inner receptacle comprising a tubular section defining the inner compartment, the said tubular section being provided at its top with a partition having solution outlet and equalizing pressure inlet means, the said partition being provided with an upstanding annular flange encircling the outlet and inlet means, the flange providing a seat for a valve.
8. An inner receptacle for a fire extinguishing apparatus of the type in which component chemical solutions are normally stored and are comixed for the production of a fire extinguishing foam, the said inner receptacle comprising a tubular section defining the inner compartment, and an integral cage member fitted to the top of the tube, the said cage member comprising vertical walls having spaced solution openings and a horizontal partition provided with solution outlet and equalizing pressure inlet means and an upstanding annular flange encircling the outlet and inlet means, the flange defining a valve seat.
9. A fire extinguishing apparatus of the type in which component chemical solutions are normally stored and are comixed for the production of a fire extinguishing medium, an outer receptacle for holding one of the component solutions, an inner receptacle for holding another of the component solutions, the outer receptacle being provided with a partition separating the said receptacle into a solution compartment and a mixing chamber; the said partition being provided with solution outlet means, the inner receptacle being also provided with a partition having solution outlet means and equalizing pressure inlet means and a discharge port opening into the said mixing chamber, the said solution outlets and the discharge port being relatively displaced to permit a predetermined volumetric intermixture of the solutions to take place in the mixing chamber.

ber with partial foam production; the solutions intermixing in the desired proportions then having egress through the discharge port.

5. 10. A fire extinguishing apparatus of the type in which component chemical solutions are normally stored and are comixed for the production of a fire extinguishing medium, an outer receptacle for holding one of the 10 component solutions, an inner receptacle for holding another of the component solutions, the outer receptacle being provided with a partition separating the said receptacle into a solution compartment and a mixing chamber; the said partition being provided with solution outlet means, the inner receptacle being also provided with a partition having 15 solution outlet means and a manually oper-

able valve means cooperating with said inner receptacle for normally closing its solution outlet means and being openable to permit solution communication from said inner receptacle to the said mixing chamber, a discharge port opening into the said mixing chamber, the said solution outlets and the discharge port being relatively displaced to permit a predetermined volumetric intermixture of the solutions to take place in the mixing chamber with partial foam production; the solutions intermixing in the desired proportions then having egress through the discharge port.

Signed at New York in the county of New York and State of New York, this 29th day of April A. D. 1921.

ORLANDO R. ERWIN.
